PROCESS OF CONVERSION OF HYDROCARBONS.

1,324,766.

Specification of Letters Patent.

Patented Dec. 9, 1919.

Application filed November 17, 1916. Serial No. 131,822.

To all whom it may concern:

Be it known that I, RICHARD FLEMING, a citizen of the United States, residing at Swampscott, in the county of Essex and 5 State of Massachusetts, have invented certain new and useful Improvements in Processes of Conversion of Hydrocarbons, of which the following is a specification.

This invention relates to a process of converting hydrocarbons of relatively high boiling point into hydrocarbons of lower boiling point, and an especial object of the invention is to obtain a product resembling natural crude oil, and containing valuable 15 lighter constituents similar to those in natural crude oil.

Although many processes have been devised for obtaining a greater yield of the low boiling point products generally known as 20 gasoline, such processes have thus far been found objectionable for one or more reasons. In some, wherein high pressure and temperature are required, it has been found difficult, if not impracticable, to build apparatus 25 capable of safely withstanding the stresses produced. In others, the expense of chemicals required prevents commercial success. In others, the processes are not continuous, and the temperatures produced are such as to 30 require frequent stoppage of the plant for cleaning, or for removing parts. In addition, many processes owing to overheating, produce an excessive amount of permanent gases, such as hydrogen and methane, with 35 or without unsaturated hydrocarbons of the aromatic or other series, which give the product an objectionable odor, leave objectionable residues when attempted to be used in internal combustion engines, and require to 40 be removed by a further and expensive treatment before the product is marketable. Where sulfuric acid is used for removing such compounds, an excess of acid is required, which increases the expense and 45 gives a relatively inferior product.

Distillation under high pressure has been employed in an effort to convert hydrocarbons from higher to lower boiling characteristics, and is moderately successful when 50 the material treated is of a sufficiently high boiling point. With the lower boiling fractions just above the gasoline fraction, these processes are not commercial, because such fractions require somewhat higher temperature for conversion than higher boiling 55

fractions, so that a sufficiently high temperature cannot be reached without an excessive pressure. At the high temperatures necessitated by high pressure distillation, the tensile strength of steel is seriously affected. Moreover, such distillation processes under high pressure are not continuous, but require large batteries of stills to be used in rotation, so that some can be cleaned while others are in use. 65

The object of this invention is to enable the conversion of higher into lower boiling hydrocarbons to be carried on continuously at approximately constant temperature and moderate pressure, whereby not only will 70 the production of gases and unsaturated compounds be a minimum, but the apparatus will not be subjected to excessive temperature or strains.

According to this invention, I treat a 75 bath or menstruum, preferably of the heaviest obtainable hydrocarbon, such as heavy fuel oils, or other heavy pitchy residues with a lower boiling hydrocarbon under moderate pressure, at a temperature above 80 350° C. A product is thereby obtained which distils over and closely resembles crude oil. When this distillate is subjected to fractionation it yields as much as 65% gasoline. The lighter boiling hydrocarbon, 85 which I use is preferably a burning oil, having a gravity of about 43° B., or what is known in the trade as water white or kerosene distillate. Such oils boil at between 180° C. and 315° C., approximately, 90 and are at present produced at the refineries largely in excess of the consumption, being either stored, or refined for burning oils, or burned for fuel, as such oils have not heretofore been economically cracked or converted, owing to having too high a vapor pressure. 95

A form of apparatus which I have found suitable is shown in the accompanying drawing, wherein 1 is a lower drum, and 2 an 100 upper drum connected by vertical tubes 3, which latter, together with as much of the lower and upper drums 1 and 2 as necessary, are heated to maintain the bath at the required temperature. 4 represents a furnace 105 from which the heat passes upwardly around part of the tubes 3 and then around the baffle 5 and downwardly and out at the stack 6, thereby causing an upward flow in the left hand tubes and a downward flow in the right 110

hand tubes. The heavy pitchy residue is constantly supplied through pipe 7 so as to maintain the bath of constant density and at the constant level 3—3, and the lighter boiling distillate is similarly supplied through the perforated pipe 8—8 located below the pipe 7 and the tubes 3 in such quantity as not to reduce the working temperature. The bottom of the drum 1 is provided with a settling chamber 10 which receives the carbon as it separates by gravity, and from which it can be drawn off as desired. This carbon can be washed with solvents and precipitated and then used for the purposes for which ordinary commercial lamp black is now employed. 11 is a gage which shows the level of the bath, 12 is a pressure gage; 13 is a vapor chamber above the level 3—3 of the bath, connected by pipe 14 containing 20 reducing valve 15, to the condensing coil 16 contained in a tank 17. The non-condensable gas and condensed vapors are drawn off at 18 and the gas separated from the vapors in the usual manner. The condensed vapors 25 are then ready for ordinary fractionation in a still under atmospheric pressure, having a color and properties resembling ordinary crude oil and yielding when fractionally distilled, a large proportion of gasoline together with heavier boiling hydrocarbons. The fractions heavier than gasoline are separated in the usual manner and used for the same purposes as the same fractions derived from the distillation of crude oil are 35 used.

The pressure is maintained at from 75 to 100 pounds, and continuous circulation is maintained by reason of the continuous feed of the materials at the bottom of the converter.

When the menstruum has reached the working temperature, a quantity of the distillate is fed therein. The pressure rapidly comes to the normal predetermined pressure and the vapors flow over into the condenser and are condensed, passing off through suitable valves into the run-down tanks, the non-condensable gases being led off to gas holders and used for fuel with or without abstraction of lighter vapors, such methods of abstraction being well known in connection with the recovery of gasoline from casing-head gas, which these gases resemble somewhat closely. The process is continuous as long as the distillates are fed to the menstruum and as long as the level of the menstruum is maintained, provided the temperatures are also maintained. The level of the menstruum is maintained by means of a pump connected to the supply of menstruum, the supply being preferably provided with a heating coil so as to maintain the contents fluid if necessary.

The circulation in the converter is rapid and is augmented by injecting the distillate

below or in advance of the ascending tubes, so that the globules of vapor ascend through the whole column of strongly heated menstruum in intimate contact therewith, and are rapidly brought to the desired temperature of conversion. It is essential that the vapors from the distillate remain in intimate contact with the menstruum for a sufficient time to complete the conversion before being released into the condensers. Under these conditions the yield or percentage of conversion would be a maximum, and this process has the important advantage of enabling these results to be very accurately controlled and to be attained with the greatest facility without danger of overheating.

In one embodiment of the invention, the menstruum is composed of pitchy residue of about 12° to 20° B., maintained approximately at its boiling temperature under the pressure used (e. g. about 400° C.), and a continuous supply and circulation is maintained under a constant pressure of from 75 to 100 pounds per square inch. Water white or kerosene distillate, of about 43° B., or heavier, boiling above 180° C. is continuously supplied through the perforated pipe 8 in quantity just sufficient to maintain the pressure, and oil distils over having light and heavy fractions, and yielding a large fraction of gasoline, when condensed and fractionally distilled. Free carbon is drawn off at the bottom as formed, and the process is maintained continuously, with a substantially constant bath, temperature, circulation and pressure as long as materials are supplied. A menstruum of 12° B. to 20° B. is suitable for use with oils boiling as high as 325° C., and for higher boiling oils it is desirable to use a still heavier menstruum according to the temperature required for conversion.

The supplies of the bath and the lighter boiling distillate can be heated before entering the converter, if desired, or the lighter boiling distillate can be supplied as vapor, but the important feature of this invention resides first, in the rapid superheating of the lighter oil distillate when it contacts in fine streams with the already hot menstruum; and secondly, in the prolonged intimate contact of this vapor with the menstruum in passing upwardly therethrough. In passing low boiling oil through the menstruum it is vaporized, and this vapor rapidly becomes superheated, independently of the pressure maintained, as distinguished from a simple distillation where the vapors are given off at their normal temperatures without being superheated.

In distilling a high boiling oil under pressure of say 100 lbs. the vapor is decomposed or "cracked" at its normal temperature corresponding to this pressure and a con-

siderable portion is found after condensation, to be converted to lower boiling characteristics. A low boiling oil is only slightly decomposed at a temperature corresponding to a pressure of 100 lbs. and unless superheated to a relatively higher temperature the amount of conversion is negligible.

By using the heavy menstruum, it is possible to attain the conversion temperature required for the lighter boiling fractions which do not contain gasolene, without raising the pressure correspondingly, and hence it is possible with this process to utilize fractions considerably lighter than gas oil, or even to use gas oil itself, as well as light fuel oils which have not heretofore been practically converted by distillation processes owing to the excessive pressures required at the necessary conversion temperatures. The menstruum not only has the function of maintaining the conversion temperature independently of pressure, thereby enabling the pressure to be varied as desired so as to obtain the best results, but enters into the reaction and is itself partly converted, being continually replenished and maintained at constant density and temperature. Apparently, the relatively complex molecules of both the lighter and the heavier boiling hydrocarbons are broken up into the simpler molecules constituting gasolene, etc.

By this process no steam, catalyzers, or desulfurizers are employed. The free carbon formation is very low by reason of the maintenance of the temperature of the bath materially below the decomposition temperature at which excess carbon and gas are formed. Owing to the continuous circulation, there is no local overheating of the tubes or other parts of the converter, and there is not at any time an exposure of a red hot tube to the vapors, which causes undesired decomposition. I have found that moderate pressure tends to reduce the formation of gases, while excess temperature, or local overheating, with or without high pressure, tends to produce unsaturated hydrocarbons, excess carbon, and gases.

From distillation at atmospheric pressure of the conversion product obtained from the pitchy residue and a water white distillate of 43° B. gravity, I have obtained 64% of crude gasolene, ready for the usual gasolene purification process. The residue from this is carried back to the converter and used in continuation of the process.

In this process, the temperature employed should not be so high as to cause extended decomposition of the menstruum, but the menstruum itself should be heavy, and be maintained approximately at its boiling point under pressure in the converting apparatus, and entirely independently of the amount of lower boiling distillate supplied

thereto. In other words, the lower boiling distillate constitutes a re-agent entering actively into the production of the product, and not a solvent or diluent of the menstruum. It is also to be noted that the menstruum and the lighter distillates employed in this process are both refinery products, so that outside materials are not required.

The invention is not restricted to any particular menstruum nor to the obtaining of gasolene, as it can also be applied to the obtaining of such unsaturated hydrocarbons as benzol, toluol, xylol, etc. Thus a menstruum composed of coal tar treated with petroleum will give a product containing large quantities of benzol and toluol, while coal tar treated with dead oil or with solvent naphtha will produce benzol, toluol and xylol, depending upon the pressure, temperature, etc.

The invention is applicable to a wide variety of distillates, and it expressly is not limited to any particular menstruum, distillate, pressure or temperature, except as stated in the appended claims.

What I claim is:

1. The process which consists in heating under pressure of approximately 75 lbs. and upward in a closed vessel a column of heavy liquid hydrocarbon to approximately its boiling point under said pressure, and passing a lower boiling hydrocarbon vapor in prolonged contact through said column of heated heavy hydrocarbon, whereby the resulting vapors are heated above the cracking point under such pressure as to retard the formation of unsaturated hydrocarbons and gases.

2. The process which consists in heating under substantially constant pressure of approximately 75 lbs. and upward in a closed vessel a column of heavy liquid hydrocarbon maintained at substantially constant height to approximately its boiling point under said pressure, and passing a lower boiling hydrocarbon vapor in prolonged contact through said column of heated heavy hydrocarbon, whereby the resulting vapors are heated above the cracking point under such pressure as to retard the formation of unsaturated hydrocarbons and gases.

3. The process which consists in passing vapor of a hydrocarbon boiling at or about 180° C. in prolonged contact with a column of liquid hydrocarbon menstruum having a boiling point at or above 350° heated in a closed vessel to approximately said boiling point under a pressure of approximately 75 pounds, and condensing the resulting vapors from the top of said vessel.

4. The process which consists in heating a column of liquid hydrocarbon menstruum having a boiling point at or above 350° C.

in a closed vessel to approximately said boiling point, passing vapor of a low boiling hydrocarbon in prolonged contact through said column of heated heavy hydrocarbon in 5 such quantity as to produce a pressure of approximately 75 pounds in said vessel, and condensing the vapors resulting from such temperature and pressure.

5. The process of cracking which consists 10 in vaporizing a hydrocarbon boiling at between 180° C. and 350° C., and passing the resultant vapors at a pressure of between 75 and 100 pounds per square inch through a hydrocarbon heated to 350° C. or upward.
- 15 6. The process of cracking which consists in heating a hydrocarbon having a gravity of 20° B. or lighter, to a temperature of 350° C. or over, and passing vapor of a distillate heavier than 45° B. therethrough at

a pressure of between 75 and 100 pounds per 20 square inch.

7. The process of producing oil having high and low boiling fractions which consists in treating a liquid hydrocarbon menstruum at or above 350° C. with superheated 25 vapor of a lower boiling hydrocarbon and under a pressure approximating 75 to 100 pounds per square inch.

8. The process which consists in heating a liquid hydrocarbon menstruum to or above 30 350° in a closed vessel while maintaining a constant level, passing vapor of a hydrocarbon boiling above 180° therethrough in a quantity tending to maintain a pressure of between 75 to 100 pounds per square inch, 35 and collecting and condensing the resulting vapors.

RICHARD FLEMING.
